CLAIM

The ornamental design for a disc case, as shown and described.

DESCRIPTION

FIG. 1 is a bottom, front and left side perspective view of a disc case according to our new design;

FIG. 2 is a bottom, rear and right side perspective view thereof;

FIG. 3 is a right side elevation view thereof;

FIG. 4 is a front elevation view thereof;

FIG. 5 is a left side elevation view thereof;

FIG. 6 is a bottom plan view thereof;

FIG. 7 is a rear elevation view thereof;

FIG. 8 is a top plan view thereof;

FIG. 9 is an enlarged view showing a portion 9 in FIG. 1;

FIG. 10 is an enlarged view showing a portion 10 in FIG. 1; and,

FIG. 11 is a cross-sectional view taken along lines 11-11 in FIG. 4.

The broken lines in the drawings show portions of the disc case that form no part of the claimed design.
